MACHINE FOR CROCHETING CORD

Morris M. Malis, Atlantic City, N. J.

Application August 20, 1949, Serial No. 111,427

4 Claims. (Cl. 66—8)

1

The machine of the present invention is designed for the production of cord from a single strand of yarn by an operation analogous to that of crocheting, and while eminently suitable for use by children as a plaything is fully capable of producing cords for the manufacture of mats, rugs, afghans and other purposes.

It is therefore a principal object of the invention to provide a machine of the character aforesaid which is adapted for manual operation and therefore of convenient size for that purpose; which is of attractive appearance; readily operable by persons of any age; capable of producing a cord of indefinite length as long as it is supplied with yarn, and comprising novel means for imparting to the latter the requisite tension as it is drawn by the needles from the source of supply.

Other objects include the provision of such machine employing two needles with means to effect their reciprocation in such way that they alternately engage and draw the yarn in a predetermined manner while they are being carried around a common axis with resultant formation of the desired cord.

Other objects and novel features of design, construction and arrangement comprehended by the invention are hereinafter more particularly pointed out or will be apparent to those skilled in the art from the following description of one embodiment of it as illustrated in the accompanying drawing in which:

Fig. 1 is an axial section of the machine in the plane of the needles which are shown in elevation;

Fig. 2 is an enlarged top plan view of the machine;

Fig. 3 is a top plan view thereof on a like scale but with the cap removed, and

Fig. 4 is a fragmentary axial section on line 4—4 in Fig. 1.

Essentially the machine includes a tubular body desirably approximating 4" in length within and axially of which is disposed a hollow rotatable needle guide the lower end of which, considering the machine in the position shown in Fig. 1 approximating that in which it is normally held when in operation, extends below the body and carries a removable circular knob by means of which the needle guide can be rotated relatively to the body by the fingers of one hand while the body itself is grasped in the other. At its other or upper end the body is provided with a removable cap embodying thread tensioning means while fixed in the body proximate its lower

2

end are two bushings within which the needle guide is journaled, these bushings being spaced apart axially at their juxtaposed edges which are so formed as to together define a sinuous cam groove for a purpose to be hereinafter described.

These several parts are preferably made of Lucite or other analogous, desirably transparent, plastic whereby the operation of the needles, the various movements imparted to the yarn and the progressive formation of the cord therefrom can be readily observed through the wall of the body. While it is of course unessential that said parts be of such material, it nevertheless is eminently desirable since it adds materially to the attractiveness and marketability of the machine.

More particularly and as hitherto stated, the body 1 is tubular and desirably of slightly greater internal diameter for approximately the upper half of its length than in its lower half within which are seated the upper bushing 2 and the lower bushing 3; I prefer to fix the former permanently in the body by means of a suitable adhesive but to make the latter a very snug but removable fit therein and prevent it from rotating by means of a key 4 or other suitable means. The lower end of the upper bushing and the upper end of the lower bushing are substantially complementary to each other, in juxtaposed spaced relation and of such shape that they form between them an endless sinuous closed groove 5 of appropriate width to receive the butts of the needles, the edge of the upper bushing, however, being shaped to provide a shoulder 6 at one point, as best shown in Fig. 4, adapted for engagement by the butt of either needle so as to prevent the needles and needle guide from being turned relatively to the body for more than a partial revolution in one direction as hereinafter described.

Rotatable within the bushings is the tubular needle guide 7 the lower extremity of which is of slightly less diameter than its major portion so as to form a shoulder which seats on an inwardly directed flange 3' at the lower end of the lower bushing; in consequence the needle guide can be drawn upwardly and removed from the body when desired, but when in operative position therein rests on flange 3'. The reduced lower end of the guide then projects below the end of the body and corresponding end of the lower bushing which is desirably flush therewith to receive a knob 8 which is bored to form a tight but removable fit upon it and is prevented from turning on the guide by a key 9 integral with the member and seating in an appropriate slot

in the end of the guide. Thus when it is desired to remove the guide from body knob 8 may be pulled off the guide to allow the latter to be drawn upwardly and out of the body as above described, and with a view to conserving material and reducing weight an annular groove 8' desirably is extended inwardly from the upper end of the knob.

The upper end of the body is operatively closed by a removable cap 10 having a peripheral flange seating on and slightly overhanging the proximate end of the body and a depending portion fitting snugly within the latter, the cap embodying the means for imparting the requisite tension to the yarn as it is drawn by the needles as hereinafter will appear.

The needle guide 7 is provided with two diametrically opposed, outwardly facing slots 11-11 extending from its upper end for the entire length of its portion of maximum diameter, the width of each of these slots being appropriate for the reception of one of the needles N, and to enable the yarn to be drawn for a short distance into the slots when the needles descend, the slots are made wider at their upper extremities as best shown in Fig. 3.

When operatively positioned in the slots the butts of the needles project outwardly into camming groove 5 (Fig. 1) with the result that when the needle guide is turned relatively to the body by means of knob 8 or vice versa the needles are respectively reciprocated in their slots so as to alternately cause their heads to rise in the vicinity of the cap, and thus into yarn engaging position, and to descend somewhat below the upper end of the guide, the needles being of usual form and provided with the customary latches for retaining the yarn within their curved heads when and as required during the crocheting operation.

To enable the butts of the needles to be entered in camming groove 5 when the parts are being assembled in operative relation, the upper bushing 2 is provided with a slot 12 extending radially through its wall from its upper edge to its lower whereby when either of the needle receiving slots in the needle guide is aligned therewith and a needle then pushed downwardly in its slot in the guide the needle butt will pass through slot 12 and thus into the camming slot; then by giving the guide a half turn so as to align the other needle slot with slot 12, the butt of the second needle may be introduced to the camming groove in like manner and thereafter as the needle guide is rotated the butts are constrained to follow the latter to reciprocate the needles as already described. However, since for proper formation of the cord it is requisite the needle guide be turned in a predetermined direction with respect to the body, namely, clockwise in Figs. 2 and 3, the shoulder 6 of which mention has been made is formed at an appropriate point in the upper wall of the camming groove whereby when the needle guide is turned in the proper direction the butts of the needles will ride over the shoulder as the cord is progressively formed during continued turning of the guide but when it is attempted to turn the guide in the opposite direction the butt of one needle or the other will very shortly thereafter contact the shoulder, thus preventing further turning of the guide in that direction.

To maintain the requisite tension on cord C as it is progressively formed and passes downwardly through the interior of the needle guide, a rod 14 having a hook at its upper end and an appropri-

ate weight 15 at its lower is engaged in the leading end of the cord immediately after its formation by the first few movements of the needles.

Mention has been made of the means associated with cap 10 for suitably tensioning the yarn Y for engagement by the needles as it is progressively drawn from a ball, skein or other source of yarn supply, said means consisting of a series of holes in the cap through which the yarn is threaded in alternate directions. More specifically, one of these holes 18 is located axially of the cap and the others, preferably two in number, are centered on a radius of the latter. These last mentioned holes, 19 and 20, as well as the axial hole are of a diameter to freely receive the yarn which, preparatory to beginning the production of the cord, is threaded through all the holes in the manner shown in Fig. 1, that is, downwardly through axial hole 18, thence upwardly through the next adjacent hole 19, and finally downwardly through the outermost hole 20. In the operation of the machine the yarn normally enters hole 18 devoid of appreciable tension but the friction exerted on it by the walls of the several holes and the intervening portions of the cap during its sinuous passage through the former produces a slight tension in it as it is drawn from hole 20 by the needles as required for the proper production of the cord. The tensioning means are thus entirely self-contained in the cap which, in turn, is a component part of the machine as a whole, and this I regard as an important feature of my invention since it entirely obviates use of any extraneous means for imparting the necessary tension to the yarn.

To insure the cap being replaced in position to bring the holes 19 and 20 into proper relation with the other parts, a key 21 is extended slightly from the depending portion of the cap which enters the body and the inner wall of the latter provided with a keyway for its reception so that when assembling the cap on the body the key must be aligned with the keyway to enable the cap to be pushed down to operative position as in Fig. 1.

In order to form a cord by the use of the machine, cap 10 is first removed and yarn Y, drawn from a suitable source of supply, threaded downwardly through hole 18, thence upwardly through hole 19 and finally downwardly through hole 20, and a knot is then formed in its end which is caught under the head of one of the needles before the cap is replaced. Thereafter relative rotation between the needle guide and the body is effected, conveniently by holding the latter in one hand and rotating the knob with the other until one or two stitches are formed. Rod 14 is then inserted upwardly through the bore of the needle guide and hooked into the leading end of the cord which is now emerging into the upper end of the bore and the weight is then attached to the lower end of the rod so as to tension the cord as it is thereafter progressively formed by the needles and draw it downwardly through the needle guide. By continuing relative rotation of the guide and body, the cord may be formed to any desired length as long as yarn is supplied, the rod and weight being moved up from time to time and hooked into the body of the cord at an appropriate point so as to maintain the requisite pull on the latter.

While I have herein described and illustrated one embodiment of my invention with considerable particularity, I do not thereby desire or

intend to restrict or confine myself specifically thereto as various changes and modifications may be made in the form, arrangement and method of assembly of the parts and the latter, save the needles, may be constructed of various materials other than transparent plastic if desired, without departing from the spirit and scope of the invention as defined by the appended claims.

Having thus described my invention, I claim and desire to protect by Letters Patent of the United States:

1. A machine for forming cords from yarn or the like, comprising a hollow body, a needle guide journaled for axial rotation therein having diametrically opposed needle receiving slots, a needle slidably positioned in each slot, means operative to reciprocate the needles when the guide is rotated relatively to the body, a removable cap closing that end of the body proximate the heads of the needles having a series of holes between its axis and periphery forming a sinuous path for the yarn effective to retard its passage therealong and thereby tension it as it is intermittently engaged by and drawn toward the needle guide by the needles.

2. A machine for forming cords from yarn or the like, comprising a hollow body, a tubular needle guide extending within and axially thereof, projecting beyond the body at one end and provided with diametrically opposed longitudinally extending slots, detachable means carried by the projecting end of the guide whereby it may be manually rotated relatively to the body, axially spaced bushings within the body forming journals for the guide and having juxtaposed edges defining between them a sinuous groove, a pair of needles respectively disposed in said slots with their butts extending into said groove and their heads proximate the other end of the guide, a cap operatively closing that end of the body adjacent the heads of the needles and provided with a central hole and a plurality of other holes spaced along a radius of the cap, the several holes and portions of the cap lying between them defining for the yarn a sinuous path extending from the central hole through the outermost hole whereby the friction exerted on the yarn as it traverses said path imparts tension to the yarn as it is drawn by the needles alternately from adjacent the outermost hole as the needle guide is rotated relatively to the body and the needles through engagement of their butts in said sinuous groove are consecutively reciprocated relatively to the guide.

3. A machine for forming cords from yarn or the like comprising a hollow cylindrical body, a tubular needle guide extending within and axially thereof, projecting beyond the body at one end and provided with diametrically opposed longitudinally extending slots, a pair of needles respectively disposed in said slots, a detachable knob carried by the projecting end of the guide whereby it may be manually rotated relatively to the body, axially spaced bushings within the body forming journals for the guide and having juxtaposed edges defining between them a sinuous groove receiving the butts of the needles, the bushing proximate the other end of the guide having in its wall a slot extending parallel to its axis and intersecting said sinuous groove to enable said butts to be introduced thereto with their heads proximate said other end of the guide, a removable cap operatively closing that end of the body adjacent the heads of the needles and provided with a central hole and a plurality of other holes spaced outwardly therefrom, the several holes and portions of the cap lying between them defining for the yarn a sinuous path extending from the central hole through the outermost one whereby the friction exerted on the yarn by the portions of the cap which it engages as it traverses said path resists free movement of the yarn therealong and thereby maintains it under tension as it is consecutively drawn by the needles alternately from adjacent the outermost hole as the needle guide is rotated relative to the body and the needles through engagement of their butts in said sinuous groove are reciprocated relatively to the guide.

4. A machine as defined in claim 3 in which the bushing proximate said projecting end of the guide is provided with a shoulder extending into the groove formed between the bushings having a face adapted to engage the butt of a needle to inhibit its passage beyond the shoulder when the needle is moving in one direction.
